FACE PLATE FOR A PLUMBING FIXTURE
OR THE LIKE

William Taylor, 2222 Malcolm Ave., Los Angeles, Calif., and Nathan Holzberg, Los Angeles, Calif.; said Holz-berg assignor to said Taylor

Filed Nov. 19, 1962, Ser. No. 72,528

Term of patent 14 years

(Cl. 91—3)

FIG. 1.

FIG. 2.

FIG. 3.

FIG. 4.

FIG. 1 is a front elevational view of a face plate for a plumbing fixture, or the like, showing our new design; FIG. 2 is a side elevational view thereof; FIG. 3 is a front elevational view of another embodiment of our new design; and

FIG. 4 is a side elevational view thereof.

The rear of both forms of the design, not shown, are flat and plain except for the open areas.

We claim:

The ornamental design for a face plate for a plumbing fixture or the like, as shown and described.
